UNITED STATES PATENT OFFICE

FREDERICK T. MOORE, OF EAST HARTFORD, CONNECTICUT, ASSIGNOR TO COLT'S PATENT FIRE ARMS MANUFACTURING CO., OF HARTFORD, CONNECTICUT, A CORPORATION OF CONNECTICUT

BARREL MOUNTING FOR FIREARMS

Application filed October 19, 1928. Serial No. 313,588.

This invention is particularly applicable to automatic machine guns of the type disclosed in the J. M. Browning patent for automatic machine guns, No. 1,293,021 dated February 4, 1919 but the invention is not necessarily so limited.

The principal object of the invention is to provide a barrel mounting for firearms of this class which permits the barrel to be readily assembled with or disassembled from the barrel extension so as to facilitate the replacement of barrels in service.

In the accompanying drawing I have shown the embodiment of the invention which I now deem preferable but it will be understood that the drawing is intended for illustrative purposes only and is not to be construed as defining or limiting the scope of the invention.

20 Of the drawing:

Fig. 1 is a side view, partly diagrammatic, of a machine gun having incorporated therein a barrel mounting embodying my invention.

25 Fig. 2 is an enlarged fragmentary plan view of the barrel and barrel extension separated from other parts of the gun.

Fig. 3 is a side view of the parts shown in Fig. 2.

30 Fig. 4 is a view similar to Fig. 3 but showing the barrel in a different position.

Fig. 5 is a rear end view of the barrel, this view being taken along the plane of the line 5-5 in Fig. 3.

35 Fig. 6 is a front end view of the barrel extension, this view being taken along the plane of the line 6-6 in Fig. 3.

Fig. 7 is a detail perspective view of the barrel latch.

40 Referring particularly to Fig. 1 of the drawing, 1 represents the breech casing of the gun and 2 the trunnion block thereof. The breech casing is provided with a cover 3 hinged at 4 to the trunnion block. At 5 there is provided an opening for the admission of a cartridge belt to the feeding and firing mechanisms which are not shown.

45 The barrel of the gun is represented at 6 and the barrel extension is represented at 7. The barrel and barrel extension move rear-

ward upon recoil and are returned to their forward positions by the mechanism of the gun following recoil movement. The barrel 6 is provided at 8 with screw threads adapted for the connection of a flash hider or a blank 55 firing device or some other attachment.

Carried by the gun at the front thereof is a means which serves to normally support the forward end of the barrel 6. I have shown for this purpose a water jacket 9 which is 60 carried by the trunnion block 2. The water jacket 9 is provided with a bushing 10 which forms part of a stuffing box to prevent the escape of water from the water jacket and which further serves as a guide for the forward end of the barrel. 65

When the barrel 6 is to be disconnected from the barrel extension 7 the said parts are first removed from the casing 1 at the rear thereof following the procedure set forth in 70 detail in the aforesaid Browning patent. In accordance with the present invention the connection between the barrel and the barrel extension is such as to permit ready detachment or re-attachment of the barrel or of another similar barrel after the parts have been removed as aforesaid. 75

The barrel extension 7 is provided at its front end with a barrel receiving opening 11 within which are formed rows or series of 80 interrupted annular ribs 12, 12. I have shown two series of ribs 12, 12 arranged opposite each other and each extending through an angle of less than 90°. I do not, however, limit myself to the provision of only two series of ribs as the number may be varied. 85

The rear end of the barrel 6 is reduced in diameter to permit it to enter the opening 11 in the barrel extension and the said reduced rear portion of the barrel is provided with 90 annular ribs 13, 13 adapted to engage with the ribs 12, 12 on the barrel extension. I have shown two series of ribs 13, 13 corresponding in number, size and shape to the ribs 12, 12 on the barrel extension. The barrel can be 95 assembled with the barrel extension by first turning it to a position approximately 90° from the position shown in Fig. 5, and moving it rearward to locate the ribs 13, 13 in the spaces between the two series of ribs 12, 12. 100

Then by turning the barrel back to the position shown in Fig. 5 the several ribs 13, 13 can be entered between the respective ribs 12, 12 thus securely holding the barrel in place. In view of the fact that the barrel is guided at the front it is not necessary for it to be rigidly or inflexibly held by the barrel extension, and in fact it is preferable to provide a limited amount of freedom permitting 10 adjustment.

In order to lock the barrel against rotative movement and to thus hold the ribs 13, 13 and 12, 12 in engagement with each other I provide a longitudinally reciprocable latch 14. For receiving the latch 14 the barrel extension 7 is provided with a longitudinal cylindrical hole 15 and the forward portion of the latch 14 is of such size as to fit the hole 15. The latch 14 includes a stem 16 at the 20 rear which is adapted to extend into a smaller hole 17 at the rear end of the hole 15. A coil spring 18 is located in the rear part of the hole 15 surrounding the stem 16. This spring tends to move the latch forward to its projecting position. For limiting the movement of the latch there is provided a transverse pin 19 which extends through a notch 20 in the stem 16.

The barrel 6 is provided with a peripheral 30 notch 21 open at the rear and a portion of the latch 14 is adapted to enter the notch to prevent rotation of the barrel. The latch 14 has another portion which projects radially outward beyond the barrel to enable the latch to be manually engaged for rearward movement out of the notch 21. As illustrated there is a radial slot 22 in the barrel extension registering with the hole 15 and the latch is provided with integral keys 23 and 24 fitting the said slot. When the latch is in its forward position as shown in Figs. 2 and 3 the inner key 23 enters the notch 21 in the barrel thus preventing the barrel from turning.

From the foregoing description it will be apparent that the barrel can be assembled with the barrel extension by simply inserting it with the ribs 13, 13 between the ribs 12, 12 and then turning it through approximately 50 90°. When the barrel is first inserted the latch 14 will be pushed rearward and the latch will automatically snap into engagement with the notch when the barrel reaches its normal position. The barrel may be disassembled from the barrel extension by first manually engaging the outer portion of the latch 14 and moving it rearward and by then turning the barrel through approximately 90° and withdrawing it. The latch 14 not 60 only holds the barrel against accidental turning but also positively resists any turning tendency resulting from the screwing into place on the threads 8, or the unscrewing of a flash hider or blank firing attachment.

65 What I claim is:

In a firearm of the character described, the combination of a main casing, a barrel guide carried by the casing and projecting forward therefrom, a barrel extension longitudinally reciprocable in the casing, the said barrel extension having at its forward end a barrel receiving opening provided with interrupted annular ribs therein and also having a smaller hole parallel with the said opening and open at the front, a longitudinally reciprocable barrel normally guided near its forward end by the said barrel guide and adapted at its rear end to enter the opening in the extension, the said barrel having interrupted annular ribs adapted upon partial rotation 70 of the barrel to enter between the annular ribs on the extension and also having a peripheral notch open at the rear and located to register with the hole in the extension when the barrel ribs are entered between the extension 80 ribs, and a reciprocable latch in the said hole in the extension spring biased for forward movement to enter the notch in the barrel and having a portion projecting radially outward beyond the barrel to enable the latch to 90 be manually engaged for rearward movement out of the said notch.

In testimony whereof I have hereunto set my hand this 18th day of October, 1928.

FREDERICK T. MOORE. 95
